UNITED STATES PATENT OFFICE

JOHN W. ALLBRIGHT, OF RIVERSIDE, CALIFORNIA

CARBURETOR

Application filed April 9, 1932. Serial No. 604,230.

My invention relates to carburetors for internal combustion engines and has particular reference to a carburetor in which the quantity of fuel and quantity of air supplied to the engine are maintained in substantially constant relative proportion independent of the speed of operation of the engine.

In the art of supplying mixed fuel and air to an internal combustion engine, many attempts have been made to maintain a constant relation between the amount of air and the amount of fuel supplied to the engine under varying conditions of operation, as, for example, by automatically increasing the fuel injection opening in accordance with the degree of suction of air through the carburetor.

However, all of these methods have been unsuccessful, due to the inability to devise an accurately graduated supply of fuel from the injection jet upon small variations in the suction through the carburetor.

It is, therefore, an object of my invention to provide a carburetor in which a fuel control valve is automatically actuated in response to the suction through the carburetor and in which actuation of the valve accurately graduates the amount of fuel supplied through the injection jet.

Another object of my invention is to provide a carburetor in which an exit is provided for an injection jet, permitting the maximum amount of fuel to pass therethrough and graduating the amount of fuel supplied to said jet in accordance with the degree of suction through the carburetor.

Another object of my invention is to provide a device of the character set forth, in which the injection of fuel into the air stream of the carburetor occurs in a Venturi tube so that the velocity of air passing through the tube causes an intimate mixing of air and fuel.

Another object of my invention is to provide a carburetor as set forth in the preceding paragraph in which the Venturi tube is adjustable relative to the opening of the injection jet to permit the setting of the venturi relative to the jet to achieve maximum efficiency.

Another object of the invention is to provide a carburetor in which a valve for controlling the amount of fuel supplied through the injection jet comprises a cylindrical valve having a plurality of progressively enlarged grooves therearound, permitting accurate graduation of the amount of fuel supplied to the jet.

Another object of the invention is to provide a carburetor of the character set forth in which fuel may be supplied to the injection jet from a float chamber or may be supplied direct from a fuel tank without the employment of a float chamber.

Other objects and advantages of the invention will be apparent from a study of the following specifications, read in connection with the accompanying drawing, wherein

Figure 1 is a vertical sectional view, taken through a carburetor constructed in accordance with my invention;

Figure 2 is an end elevational view, shown partly in section, of the carburetor illustrated in Figure 1;

Figure 3 is a detail view of the construction of a fuel supply valve, which may be employed in the practice of my invention; and

Figure 4 is an end elevational view of a modified form of carburetor which may be employed in the practice of my invention.

Referring to the drawing, I have illustrated in Figure 1 a carburetor having a body member 1, illustrated as being substantially cubical in configuration to form a housing chamber 2 in which an injection jet 3 may be mounted. The injection jet 3 is preferably formed of a T-shaped tubular member 4 threadedly secured at one end 5 thereof into a plate 6 constituting one side of the body member 1. If desired, the plate 6 may be formed separately from the body member 1 and attached thereto as by means of screws 7, the plate being provided with an inwardly extending shoulder 8 engaging the periphery of a circular recess 9 formed in the material of the body member 1.

By referring particularly to Figure 2, it will be observed that the cross member 10 of the T is directed substantially at a right

angle to the axis of the threaded portion 5 and constitutes a fuel entrance 11 to which may be connected one end of a fuel supply pipe 12. The tubular member 4 is illustrated as having an upstanding boss 13 thereon extending at right angles to both the threaded section 5 and the cross member 10 to constitute a mounting device for the injection jet outlet 14. The outlet 14 is illustrated as being formed of substantially tubular shape, having a fuel passage 15 therethrough extending into communication with the interior of the tubular member 4 and having its outer end terminating in a flared opening 16. Preferably, the fuel passage 15 is of such size as to accommodate the maximum quantity of fuel which will be required for the engine under maximum conditions of speed and load.

20 The jet outlet 14 is illustrated as extending along the axis of a tubular mixture outlet 17 which may be connected by means of a flange 18 to the usual inlet manifold of the internal combustion engine with which my carburetor may be associated. The outlet 17 may be provided with the usual butterfly throttle valve 19 employed for controlling the amount of mixture admitted to the engine.

25 30 It will also be observed that the mixture outlet 17 is provided with an inner tube 20 fitted within the passage through the mixture outlet 17, the inner walls of the inner tube 20 being of such configuration as to 35 constitute a Venturi tube through which air and fuel must be drawn into the engine. It will be observed that the outer walls of the tube 20 conform with the inner walls of the outlet 17 so that the tube 20 may be adjusted 40 to any position along the length of the outlet 17. Thus the nearest portion of the venturi may be located immediately above the fuel injection outlet, or may be adjusted some distance above the same, or may be adjusted 45 below the same to provide the constriction of the passage therethrough at the most desirable point to insure maximum suction of fuel through the passage 15 and to insure the maximum mixing effect between the air and 50 fuel.

An air entrance inlet 21 is illustrated communicating with the interior chamber of the body member 1, the air entrance inlet being preferably formed upon a nipple 22 threaded into one side of the body member 1, as is indicated at 23. Mounted upon the outer end of the nipple 22 I have illustrated a choke assembly 24 including a tubular entrance housing 25 in which is mounted the usual butterfly valve construction 26 employed to close the air entrance when it is desired to "choke" the carburetor.

In order to properly coordinate the amount of fuel which is supplied to the engine in accordance with the amount of air supplied to

the engine, a fuel control valve 27 may be employed, mounted in and slidable along the body member 4 of the injection jet assembly. The valve 27 is illustrated as being provided with a plurality of annular grooves 28, the grooves toward the right hand end of the valve 27 being relatively large, while the size of the grooves progressively diminish as they approach the left hand end of the valve 27. Each of these grooves may be selected of such dimensions as will permit the flow therearound of a predetermined quantity of fuel under conditions of substantially constant pressure.

From an inspection of Figure 1, it will be observed that the fuel entrance 11 to the jet 4 lies in the same vertical plane as the fuel passage 15 of the injection outlet 14, so that at the instant that any one of the grooves 28 is aligned with the fuel entrance, the same groove is aligned with the fuel passage 15 so that the amount of fuel which may pass around that particular groove is the amount of fuel supplied to the fuel passage 15.

By referring to Figure 1, it will be observed that the fuel valve 27 is normally pressed toward the right, as shown in this figure, by means of a compression spring 29, seated in a suitable recess 30 formed in the end of the valve 27, the other end of the spring bearing against the head 31 of an adjusting screw 32 by which the compression of the spring 29 may be regulated. Thus the valve 27 is normally pressed toward the right to align the smallest of the grooves 28 with the fuel passage 15 and thereby normally limit the quantity of fuel supplied to the minimum amount.

It will also be observed that the right hand end of the valve 27 is provided with an annular cap 33 constituting an air valve normally seated upon a valve seat 34 located in the air entrance nipple 22 so that when the valve 27 is pressed to the right by means of this spring, the cap 33 will seat upon the seat 34 to substantially close the air inlet to the carburetor. If desired, suitable small openings 35 may be formed in the cap 33 to permit the ingress of a sufficient amount of air to supply an idling mixture to the engine, even though the cap 33 is seated upon the seat 34.

With the construction herein described, it will be observed that normally the valve 27 is in such position as to provide the minimum quantity of fuel to be injected into the carburetor, while the openings 35 in the cap 33 permit the ingress of just the correct amount of air for such minimum amount of fuel to maintain the idling speed of the motor to which the carburetor is attached.

However, as the throttle valve 19 is opened for the purpose of speeding up the engine, the increased suction will cause the cap 33 to be drawn inwardly (that is, to the left, as

viewed in Figure 1), by the suction created in the mixing chamber, and when so drawn the valve 27 will automatically assume a position corresponding to the degree of suction 5 through the carburetor. This operation will cause another of the grooves 28 to be aligned with the fuel passage 15, corresponding to the amount of suction in the carburetor. By properly adjusting the spring 29 to the suction 10 of the particular engine to which my carburetor is attached, the particular groove aligned with the fuel passage at any given value of suction may be of just the correct size to supply the right quantity of fuel for 15 the corresponding amount of air passing through the carburetor.

It will be further observed that by employing the annular grooves in the valve 27, any desired graduation in size between adjacent 20 grooves may be employed so that accurate graduations of the amount of fuel supplied may be obtained, as distinguished from the employment of an ordinary needle or tapered valve construction in which relatively 25 small amounts of longitudinal movement of the valve member causes a relatively great change in the orifice between the valve and the seat preventing minute and accurate graduations of the fuel opening.

It will be observed that the valve seat 34 30 may be adjusted manually along the line of movement of the valve 27 to thereby permit adjustment of the seating of the fuel valve 27 to correspond to the degree of suction created by any particular engine. This permits the adjustment of the idling speeds and also permits adjustment of the quantity of fuel supplied to the engine in accordance with the character of the engine to which the device is 40 attached.

In the embodiment of my invention shown herein, the carburetor is adapted to what is known as the "updraft" type of mixture inlet; that is, the carburetor is illustrated as 45 having the stream of air drawn into the carburetor and then drawn upwardly into the engine. By employing a body member of the character set forth herein, my carburetor is equally adapted to a down draft system, without altering the point of fuel entrance into 50 the carburetor. This is accomplished by providing the upper and lower walls of the body member with relatively large openings 36 and 37 therethrough, these openings preferably being of the same dimensions and 55 preferably being circular, so that the mixture outlet tube 17 may be removed from the top of the carburetor housing and be placed upon the bottom thereof, while the bottom closure plate 38 may be removed from the bottom and placed upon the top of the carburetor housing to close the opening 36.

In like manner the mixture outlet tube 17 60 may be placed upon the side of the carburetor in the opening 39 therein, if it is desired that the outlet shall lead from the side

of the carburetor instead of from the top or bottom.

It will also be observed that the jet tube member 4 has a downwardly extending boss 40 in alignment with the boss 13 so that the fuel outlet 14 may be inserted in the opening 40 instead of the opening 16 in the event the carburetor is used for down draft. A suitable screw plug 41 may be employed to close the opening through the bosses 40 or 13, respectively, which is not in use.

By referring particularly to Figure 2, it will be observed that the employment of the Venturi tube 20 will permit the suction of the incoming air to suck fuel through the fuel passage 15 and this suction may be so great as to draw fuel direct from the suitable fuel tank, it being preferable to provide a suitable reservoir 42 near the carburetor to maintain therein some fuel to permit easy starting. This reservoir may be comprised of a coil of the fuel supply tube, if desired, and is preferably provided with a check valve 43 preventing back draining of the fuel from the reservoir when the engine is stopped, thereby retaining fuel in the reservoir for starting purposes.

Also, if desired, my carburetor may be employed with the ordinary float chamber reservoir, as shown in Figure 4, the reservoir being indicated by the reference character 44 formed upon a suitable plate 45 which may be substituted for the plate 46 shown in Figure 2, so that the reservoir 42 may be removed from the carburetor and the float chamber 44 inserted in place thereof if it is desired to float-feed the system for the carburetor.

While I have shown and described the preferred embodiment of my invention, it is to be understood that I do not wish to be limited to the details of construction shown herein, except as defined in the appended claims.

I claim:

1. In a carburetor, means defining an air passage through said carburetor, a fuel injector in said passage for admitting fuel to a stream of air passing through said carburetor, said injector having a fuel inlet and a fuel outlet spaced from each other, a valve for variably controlling the quantity of fuel injected into said air stream, having a valve stem formed with a plurality of grooves, each of which is selectively alignable with both the fuel inlet and the fuel outlet and each of which is formed with a different area.

2. In a carburetor, means defining an air passage through said carburetor, a fuel injector in said passage for admitting fuel to a stream of air passing through said carburetor, said injector having a fuel inlet and a fuel outlet spaced from each other, a valve for variable controlling the quantity of fuel injected into said air stream, having a valve

- system formed with a plurality of grooves, each of which is selectively alignable with both the fuel inlet and the fuel outlet and each of which is formed with a different area, 5 and means operably responsive to the pressure of air passing through said passage for moving said valve stem to bring any one of said grooves into alignment with said fuel inlet and fuel outlet corresponding to the 10 pressure of the air.
3. In a carburetor, means defining an air passage through said carburetor, a fuel injector in said passage for admitting fuel to a stream of air passing through said carburetor, said injector having a fuel inlet and 15 a fuel outlet spaced from each other, a valve for variably controlling the quantity of fuel injected into said air stream having a valve stem formed with a plurality of spaced grooves thereon, each of which is formed 20 with a different area diminishing as said groove is spaced further from one end of said valve stem, and operating means for said valve interposed in said air stream for movement by said air stream to move said valve stem to present increasingly large area 25 grooves to said fuel inlet and outlet as the pressure of said air stream increases.
4. In a carburetor, a body member forming 30 an air passage through said carburetor, a fuel injector in said body member for admitting fuel to a stream of air passing therethrough, said injector having a fuel inlet and 35 a fuel outlet spaced from each other and having a valve for variably controlling the quantity of fuel injected into said air stream including a valve stem having a plurality of spaced circumferential grooves therearound 40 each alignable with said fuel inlet and said fuel outlet to provide a passage therebetween, each of said grooves being of a different area, an air inlet in said body member, means on said valve stem adjacent said air inlet for 45 closing said air inlet and operable in response to pressure of air entering said body member for moving said valve stem relative to said fuel inlet and outlet to align any one of the grooves thereon with said fuel inlet and outlet; depending upon the pressure of air passing 50 through said air inlet.
5. In a carburetor, a body member forming 55 an air passage through said carburetor, a fuel injector in said body member for admitting fuel to a stream of air passing therethrough, said injector having a fuel inlet and a fuel outlet spaced from each other and having a valve for variably controlling the quantity of fuel injected into said air stream including 60 a valve stem having a plurality of spaced circumferential grooves therearound each alignable with said fuel inlet and said fuel outlet to provide a passage therebetween, each of said grooves being of a different area, 65 an air inlet in said body member, an air valve 70 on said valve stem, a seat for said valve located in said air inlet whereby pressure of air entering said inlet will move said air valve from said seat to align any one of the grooves on said valve stem with said fuel inlet and fuel outlet depending upon the pressure of said air, and means for adjusting said air valve seat toward and away from said injector to normally align any one of said grooves with said fuel inlet and outlet to thereby adjust the quantity of fuel supplied to said carburetor for "idling" operation.
